ALLEN HOOVER DINGMAN, OF ALLISON PARK, PENNSYLVANIA, ASSIGNOR OF ONE-HALF TO HERMAN KAPPELER, OF ALLISON PARK, PENNSYLVANIA.

SPARK-PLUG.

1,130,494.

Specification of Letters Patent.

Patented Mar. 2, 1915.

Application filed April 23, 1914. Serial No. 834,030.

To all whom it may concern:

Be it known that I, ALLEN H. DINGMAN, a citizen of the United States, and a resident of Allison Park, in the county of Allegheny and State of Pennsylvania, have invented 5 a new and Improved Spark-Plug, of which the following is a full, clear, and exact description.

The invention relates to spark plugs used 10 in connection with internal-combustion engines.

The object thereof is to provide a simple, 15 inexpensive and efficient plug which is light in weight and which is moisture and oil proof.

I attain the above object by the structure illustrated in the accompanying drawings forming a part of the specification and in which similar characters of reference indicate corresponding parts in all the views 20 and wherein—

Figure 1 is a face elevation of a spark-plug embodying my invention; Fig. 2 is a side elevation of the same; Fig. 3 is a plan view of the threaded member carrying the plug proper, whereby the same is secured; Fig. 4 is a horizontal section on line 4—4, Fig. 1; Fig. 5 is an elevation of the casing with the cover removed; Fig. 6 is a face elevation of the cover for the casing; Fig. 7 is an elevation of an insulating member; Fig. 8 is a section on line 8—8, Fig. 1; Fig. 9 is an enlarged view of the lower end of the electrode; and Fig. 10 is a section on line 35 4—4, Fig. 1, showing a modified structure of the interior of the plug.

Referring to the drawings, 11 represents a shallow elongated casing having the shape of a keystone, the ends of which are rounded. 40 A cover 12 is fitted snugly into the casing and forms one face of said casing, the other face being formed by the bottom of the casing, the edges 13 of the casing forming the sides thereof. Positioned in the casing is 45 a flat, elongated electrode 14 to the lower end of which is clamped a platinum member 15 which is disposed transversely of said electrode with the end 16 thereof perpendicular to the faces of the electrode 15. The 50 faces of the lower end of the casing are provided with angular apertures 17 through which the ends 16 of the platinum member project centrally, so as to be evenly spaced from the edges formed by said apertures 17.

The electrode 14 and the platinum member 55 15 are spaced from the bottom of the casing and from the cover thereof by insulating members 18 which fit snugly into the casing and which are of substantially the same contour as the cover 12. The ends 16 of the 60 platinum member 15 are made to project through said insulating members 18. The upper end of the electrode 14 is connected to a head 19 of a screw 20. The head 19 is set into a fibrous washer 21 which is received 65 in an opening 22 formed in the cover 12. The edges of the opening are preferably raised, as shown at 23 in Fig. 8, so as to give a larger surface of contact between the washer and the sides forming the opening 70 22. As shown in Fig. 8, the opening 22 tapers toward the exterior of the casing so as to lock the washer therein when the casing is closed by the cover.

The thickness of the electrode and the insulating members is such that when the same are placed into the shallow casing 11 and the cover placed thereon, the outer face of the cover is below the edges 13; and the edge is then turned down by suitable means 75 under high pressure thus hermetically sealing the casing at the edges (see Fig. 4). The aperture 17 through which the ends 16 of the electrode project each, preferably, receives a drop of fused insulation enamel to 80 prevent oil in the cylinder from working back between the layers of insulating material and producing a short circuit therein. It is self-evident that any other fusible slag can be used in lieu of the enamel used for 85 glazing.

The hermetically closed casing is received in a keystone slot 24 provided in a threaded member 25, with the lower end of the casing projecting below the threaded member, and 90 the upper end remaining above the threaded member. The casing is secured to the threaded member in any suitable way, such as brazing or welding. The screw 20 receives a fiber washer 26 and a thumb nut 27, 95 whereby an electric conductor 28 may be connected to the screw and, therefore, to the electrode.

In the modified structure shown in Fig. 10, the casing 11' has its interior enameled; 100 and the inner surface of the cover 12' is also enameled. This insulates the inner surfaces of the casing, and the electrode 14', in

this case, can be wrapped in asbestos in lieu of using mica which is generally used for insulators. Furthermore, the entire space in the casing between the cover and the bottom 5 thereof can be filled with asbestos wool, as indicated by 29, so as to form a perfect insulating packing, as shown in Fig. 10. It is self-evident that, if desired, the inner surfaces of the casing can be glazed, even when 10 using mica, as the enamel greatly improves the insulating quality of the casing, thus insuring the insulation of the electrode from the casing.

From the above it will be seen that in my 15 spark-plug the insulation protecting the electrode from the casing is inclosed in a hermetically sealed casing and is, therefore, not affected by the moisture of the atmosphere nor by the gases of the cylinder, as 20 the openings 17 receive enamel which prevents the gases from entering the casing, as previously described, and also prevents the oil from working therebetween. This structure, therefore, insures a permanency to 25 the spark-plug. Furthermore, the ends 16 of the electrode being disposed on each side of the casing give a large area of action and insure a positive spark in the gap formed between the ends 16 and the outer edges of 30 the apertures 17.

Having thus described my invention, I claim as new and desire to secure by Letters Patent:

1. In a spark-plug,—an elongated shallow 35 casing, an electrode in said casing; means insulating the electrode from the casing, said casing having apertures at the lower end thereof through which the electrode ends project; means insulated from the casing 40 adapted to connect the conductor to the electrode; and means carrying the casing whereby the same can be secured.

2. In a spark-plug,—an elongated, shallow casing; an electrode in said casing; means 45 sealed in the casing insulating the electrode from the casing, said casing having apertures in the faces at the lower end thereof, said electrode having terminals projecting through the apertures in the faces and from 50 which the same is separated by a spark gap; and a binding post from the electrode at the

upper end of the casing and insulated therefrom.

3. In a spark-plug,—a shallow, keystone-shaped casing; an electrode in said casing; means sealed in the casing insulating the electrode therefrom, said casing having apertures in the faces at the narrower end thereof, said electrode having terminals projecting through the apertures in the faces 60 and spaced from said apertures by a spark gap; a binding post for the electrode at the wider end of the casing and insulated therefrom; and means associated with the casing whereby the same may be secured. 65

4. In a spark-plug,—a shallow, keystone-shaped casing rounded at the ends, said casing being enameled interiorly; an electrode in the casing; means sealed in the casing insulating the electrode from the casing, said 70 casing having apertures in the faces thereof at the narrower end of the casing, said electrode having terminals projecting through the apertures; a binding post associated with the electrode at the wider end of the casing 75 and insulated therefrom; and means carrying the casing whereby the same can be secured.

5. In a spark-plug,—a shallow, keystone-shaped casing; an electrode in said casing; means sealed in the casing insulating the electrode from the casing, said casing having apertures in the faces thereof at the lower end, said electrode having terminals projecting through the apertures; said insulating means sealing the bottom of the 80 apertures adjacent the electrodes; and means associated with the casing whereby the same can be secured. 85

6. In a spark plug, a key-stone shaped 90 casing enameled interiorly, an electrode in said casing, said electrode and casing having terminals separated by a spark gap, and insulating means in the casing enveloping the electrode. 95

In testimony whereof I have signed my name to this specification in the presence of two subscribing witnesses.

ALLEN HOOVER DINGMAN.
